SIMULTANEOUS POSITION SWITCH
Russell E. Brock, Jr., 8 Chester Ave., Rome, Ga.
Filed Nov. 21, 1961, Ser. No. 153,913
4 Claims. (Cl. 200—5)

This invention relates generally to electrical switches and more particularly to simultaneous position switches.

It is an object of the present invention to provide a simultaneous position switch offering positive and trouble free performance.

Another object of the present invention is to provide a simultaneous position switch having a selector rod which selectively makes electrical contact at the places required.

Other objects of the invention are to provide a simultaneous position switch bearing the above objects in mind which is of simple construction, has a minimum number of parts, is inexpensive to manufacture and efficient in operation and use.

For other objects and for a better understanding of the invention, reference may be had to the following detailed description taken in conjunction with the accompanying drawing, in which:

FIGURE 1 is a longitudinal cross sectional view of the present invention;

FIG. 2 is a top elevational view thereof.

Referring now to the drawing in detail, the numeral 10 represents a simultaneous position switch according to the present invention wherein there is a case 11 of generally cylindrical configuration. The lower portion of the outer cylindrical surface 12 is provided with a thread 13 which is threadedly engaged with a mounting adaptor 14. The adaptor 14 has a thread 15 on its outer side which is engageable with corresponding parts when mounting the present switch in a panel. The adaptor 14 is provided with an outwardly extending flange 16, the underside of which bears against the front face of the panel. The top end of the case is provided with a wall 17 through which there extend a plurality of contact elements 18. A solder lug 19 is affixed to each of the said contact elements in order to attach an electrical wire 20 thereto. Thus, the top plate serves as a support plate for the contacts. A like number of contact elements 21 extend through openings 22 within the support plate. The outward ends of the contact elements are connected to wires 23 as shown in FIG. 1 of the drawing. A guide plate 24 is affixed in permanent position relative to the sides of the case and is provided with a large central opening 25 and radially disposed openings 26, adjacent each of the openings 26 is a notch 27 within which the lower end of the contact element 21 is placed.

A sliding contact element 28 extends upwardly through the opening 26, the sliding contact being in alignment with the contact 18 in the support plate. The contact element 28 is comprised of a longitudinal shank upon which collars 29 are fixed at its lower end and collars 30 are affixed at an intermediate position. A spring 31 is located between the collar 30 and the underside of the guide plate 24, the spring 31 being in tension and normally urging the said movable contact downwardly.

A yieldable spring 32 is affixed to the interior side 33 of the case, the spring being in the path of travel of the collar 29, the spring forming a stop for the collar when the same overrides the spring upwardly.

Within the center of the case is a cylindrical element 33 slidable within said case and having an outwardly extending flange 34 integral therewith. A compression coil spring 35 bears between the upper side of the flange and the lower edge of the case. The element 33 is provided with a bottom wall 36 having an enlarged central opening 37 through which there extends a selector rod 38. The upper end of the selector rod 38 is provided with a

2

flange 39 which bears against the upper side of the opening 25 in the guide plate 24. A collar 40 is rigidly affixed to the selector rod and a compression coil spring 41 bears between the upper side of the collar 40 and the underside of the guide plate 24. A sidewardly projecting arm 42 is permanently affixed to the selector rod.

In operation the selector rod is rotated to the position desired and moved upwardly. This causes the projecting arm 42 to depress the movable contact 28 by bearing against the collar 29. Affixed to the contact shank, upon being moved, the contact 28 engages contact 18. At this point the collar has overridden upwardly past the spring stop 32 and is releasably held therebehind. The selector rod is returned to its normal position again by means of the spring 41 bearing against the underside of the guide plate 24. The contact is now complete between the wires 23 and 20. To place the switch into the "Off" position again, selector rod is in the position indicated, the element 33 is depressed. This forces the upper edge of the element 33 to bear against the spring clip stop 32 forcing the same toward the wall, thereby permitting the collar 29 on contact 28 to be returned downwardly due to the action of the coil spring 31. The element 33 is then returned downwardly again due to the action of the coil spring 35 against the flange 34.

While various changes may be made in the detail construction, it shall be understood that such changes shall be within the spirit and scope of the present invention as defined by the appended claims.

30 What I claim as new and desire to protect by Letters Patent of the United States is:

1. In a simultaneous position switch the combination of a case of cylindrical configuration, the lower portion of said cylinder being threaded and an adaptor threadedly secured thereto, the upper end of said cylinder comprising a support plate, a plurality of contacts disposed in circular arrangement and extending through said support plate, solder lugs affixed to each of said contacts on the upper surface of said support plate, a plurality of movable contacts below said contacts mounted in said support plate, each of said movable contacts electrically connected to a plurality of upstanding contacts, said upstanding contacts extending upwardly through said support plate in concentric arrangement respective to first said contact, said first contact and said movable contacts being in alignment with each other and an internal cylindrical element slidable within the first said cylinder, said cylinder element having a central opening in a bottom wall thereof, said upper cylinder, support plate having a guide plate therebelow, a central opening in said guide plate, a longitudinally extending selector rod extending through said openings in said guide plate bottom wall of said inner cylinder element, said selector rod being rotatable and having an outwardly extending arm for urging upwardly any preselected movable contact for engagement with first said contacts in said support plate.

2. In a simultaneous position switch the combination as set forth in claim 1 wherein said selector rod has an outwardly extending flange adjacent its upper edge and above said opening in said guide plate a collar affixed around said selector rod at a point between the opposite ends thereof a compression coil spring between the upper side of said collar and the lower side of said guide plate.

3. In a simultaneous position switch the combination as set forth in claim 2 wherein each of said movable contacts comprises a longitudinally extending shank extending through openings in said guide plate, a collar affixed to said shank near its lower edge, a second collar affixed to said shank at a point between opposite ends of said shank, the upper end of said shank having an enlarged head forming a contact, said enlarged head being above the opening in said guide plate and a compression coil

spring between the upper side of the latter said collar and the lower side of said guide plate.

4. In a simultaneous position switch the combination as set forth in claim 3 wherein the first said cylinder has a plurality of spring stops affixed to the interior sides thereof, said spring stops extending in the path of said lower collar of said movable contact and said inner cylinder element having an upper edge engageable with said spring stops for retraction thereof to release said movable contact, said inner cylinder element being normally urged downwardly by means of a compression coil spring be-

5 tween the lower edge of the first said cylinder and an outwardly extending flange affixed to said inner cylinder element.
